UNITED STATES PATENT OFFICE.

JOHN H. RHAMY, OF ANTIOCH, INDIANA.

WHEEL-CULTIVATOR.

SPECIFICATION forming part of Letters Patent No. 230,057, dated July 13, 1880.

Application filed March 9, 1880. (No model.)

To all whom it may concern:

Be it known that I, JOHN H. RHAMY, of Antioch, in the county of Huntington and State of Indiana, have invented certain new and useful Improvements in Wheel-Cultivators; and I do hereby declare that the following is a full, clear, and exact description of the same, reference being had to the accompanying drawings, in which—

10 Figure 1 is a plan view of a wheel-cultivator embodying the improvements in my invention. Fig. 2 is a side elevation of the same; and Figs. 3, 4, 5, 6, and 7 are sectional detail views of various parts of the machine. Fig. 8 is a rear elevation of my improved wheel-cultivator.

15 This invention has relation to wheel-cultivators; and it consists in the improved features of construction hereinafter fully described, and particularly pointed out in the claims.

20 Referring by letter to the drawings, A designates the central arch, to the arms of which are secured the half-arches B by clamp-bolts at V and head-blocks W. Curved arms C are hinged to the lower ends of the arms of the 25 half-arches B, and the journals for the wheels D are made in the outer ends of said arms C. The arms of the central arch, A, are bent outward and horizontally, and are passed through hinge-boxes E to form the axle. Half-joints

30 F, square shouldered upon the inside and round shouldered upon the outside, are hinged to the boxes E. The plow-beams are curved upwardly, as shown, and their front ends are bolted to the hinge-joints F.

35 A rear arch, M, is fastened at the top by clamp-bolts to the central arch, A, and at the bottom to the tongue. One end of each of the chains N is fastened to the plow-beam. The chains are then passed over pulleys O at the 40 top of the rear arch, M, and the other end of each chain N is fastened to a weight, P, sliding on the arms of the arch M. These weights P carry the natural weight of the plows, thereby making the plows easy to handle, and when 45 the plows have been elevated above the balancing-point the weights will hold them in such elevated position.

In plowing small corn the sides of the double tongue Q should be fastened together at 50 their front ends to form a single tongue, and to compensate for the shortening of the hinged

neck-yokes R, with which the sides Q of the double tongue are provided, I construct said neck-yokes R in two sections, provided with perforations through which screw-bolts may 55 be passed, in order that said yokes may be shortened or lengthened by adjustment, as occasion may require, as is plainly shown in section in Fig. 4.

In plowing high corn, either before or after 60 maturity, the sides Q of the double tongue are separated at their front ends by a front arch, S, and the yokes R are shortened by adjustment in accordance therewith.

The single-trees G are fastened to the ends 65 of a chain, H, which passes under pulleys I, connected with clevises X on the arms of the half-arches B, over pulleys J, secured to the head-blocks W, under pulleys K at the tops of the half-arches B, and over pulleys L at the 70 top of the central arch, A. Where the horses are unequal in strength I make the pulley I on the side at which the stronger horse is placed smaller than the opposite pulley I, which gives the weaker horse an advantage and equalizes 75 the draft. By this construction the single-trees, pulleys, and chain H are all out of the way of the corn, and will pass it without injury to it.

The curves in the plow-beams permit the 80 wheels D to pass under them when necessary in turning at the ends of the rows and in avoiding stumps and like obstructions. The half hinge-joints F permit the plows to play outward but not inward. The hinge-arms C permit the wheels D to turn in any direction.

The plows can be easily thrown either to the right or left by the plowman, so that he will be enabled to throw the dirt evenly to each side of the hill, regardless of its position in the 90 row, even though the row be crooked and the hill out of place in the row.

In turning at the ends of the row it will be unnecessary to back the team or pull back the plows, because, when the team starts in upon 95 the next row, the plows can be immediately and easily thrown into place by the plowman.

In plowing tall corn the following directions should be observed and followed: Loosen the right chain N from its weight P and attach it 100 to the lever T, which is fastened to the tongue, as shown in an enlarged view in Fig. 3. Then

move the right-hand pulley O to the center of the arch M, as shown at U in Fig. 1. This change converts the lever T into a handle for the right-hand plow and throws the handles 5 for both plows upon the left-hand side of the row. The front arch, S, and the shortened neck-yokes R should be now employed on the double tongue. Tie the off horse back by a strap attached to the ring Y, and hold him to the right by a jockey-stick, and drive the near horse with a single line. In this manner high corn can be plowed with comparative ease without injury to the corn. In this instance the hinge-arms C must be made rigid.

15 Having thus fully described my invention, what I claim as new and useful, and desire to secure by Letters Patent, is—

1. In a wheel-cultivator, the central arch, A, and half-arches B, in combination with the 20 wheels D, connected to the half-arches B by hinge-arms C, and the curved plow-beams connected to the arch A by hinge-boxes E and

half hinge-joints F, substantially as and for the purposes set forth.

2. In a wheel-cultivator, the plow-beams 25 hinged to the arch A, as shown and described, in combination with the chains N, arch M, and weight P thereon, substantially as and for the purposes set forth.

3. In a wheel-cultivator, the plow-beams 30 hinged to the central arch, A, by boxes E and joints F, as described, in combination with the chains N, weight P, and lever T, substantially as and for the purposes set forth.

4. In a wheel-cultivator, the double tongue 35 Q, Q, pivoted or hinged to the arch A, as shown, in combination with the hinged adjustable neck-yokes R R and the front arch, S, substantially as and for the purposes set forth.

JOHN H. RHAMY.
